UNITED STATES PATENT OFFICE.

FRED R. PATCH, OF SUTHERLAND FALLS, VERMONT, ASSIGNOR OF ONE-HALF TO REDFIELD PROCTOR, OF SAME PLACE.

MACHINE FOR RECIPROCATING TOOLS.

SPECIFICATION forming part of Letters Patent No. 297,839, dated April 29, 1884.

Application filed January 11, 1884. (No model.)

To all whom it may concern:

Be it known that I, FRED R. PATCH, of Sutherland Falls, in the county of Rutland and State of Vermont, have invented a new and Improved Machine for Reciprocating Tools, of which the following is a full, clear, and exact description.

The object of my invention is to provide a new and improved machine for reciprocating tools for cutting and drilling stones, wood, or other material, which machine is very simple in construction.

The invention consists in the combination with two cylinders, each having an open and a closed end, and the ends of the cylinders being connected by a tube, of pistons contained in the cylinders, and piston-rods projecting from the open ends of the cylinders. One of the pistons is reciprocated, and the pressure of the one reciprocates the other piston to which the tool is fastened.

The invention also consists in various parts and details and combination of the same, as will be fully described and set forth hereinafter.

Reference is to be had to the accompanying drawings, forming part of this specification, in which similar letters of reference indicate corresponding parts in all the figures.

Figure 1 is a longitudinal elevation of my improved machine for reciprocating tools, parts being broken out. Fig. 2 is a longitudinal sectional elevation of the same. Fig. 3 is a longitudinal sectional elevation of a modification of the same.

A cylinder, A, open at one end, has its opposite end connected by a tube, B, with the end of a cylinder, C, the opposite end of which is open. The cylinders A and C are surrounded by larger casings A' and C', respectively, which are closed at the outer ends, and the said casings A' and C' are connected by a tube, D, surrounding the tube B. The cylinders A and C contain the pistons E and F, respectively, the piston-rods E' and F' projecting from the upper ends of the cylinders and through the heads on the ends of the casings A' and C'. The piston-rod E' is provided with a transverse slotted bar, G, through which a pin, H, passes into a wheel, J, whereby the piston-rod will be reciprocated by turning the

wheel, or the said piston-rod can be connected with any other suitable devices for reciprocating it.

On the head, at the outer end of the casing C', a guide-tube, K, is screwed, through which the piston-rod F' passes, which rod is provided at its outer end with a socket, L, for receiving the butt-end of the tool M. The tube B is provided with a valve, Q, near the cylinder C. The tube K is surrounded by a handle-piece, N.

In the construction shown in Fig. 3 the casings A' and C' and the tube D are dispensed with, and the outer end of the cylinder C is provided with a head, P, having apertures Q, or the outer end of the cylinder C can be left open, as shown in Fig. 2.

The tool can be dropped at any time, or its movements regulated by the valve O. The tubes B and D are preferably made of rubber.

The operation is as follows: If the piston E in the cylinder A is moved in the direction of the arrow a', the air will be forced out of the open end of the cylinder A through the casing A', the tube D, and the casing C', into the open end of the cylinder C, and will force the piston F in the direction of the arrow a', a partial vacuum being formed in the cylinder A and the tube B. If the piston E in the cylinder A is forced in the inverse direction of the arrow a', the air in the cylinder A and in the tube B is compressed and forces the piston F in the inverse direction of the arrow, the air in the cylinder C being forced out at the open end of the cylinder C and passing through the casing C', the tube D, and the casing A' into the open end of the cylinder A, and so on alternately, whereby the tool M will be reciprocated.

In the device shown in Fig. 3 the operation is similar, and is as follows: If the piston E is moved in the direction of the arrow a', the air is forced out of the cylinder A at the open end, and a partial vacuum is formed in the closed end of the cylinders A and C. Thereby the piston F is moved in the direction of the arrow a'. If the piston E is moved in the inverse direction of the arrow a', the air in the cylinder A is compressed and forces the piston F in the cylinder C in the inverse direction of the arrow a'.

the arrow a' , the air in the cylinder C being forced out through the apertures Q, and the air entering the cylinder A at the open end, and so on alternately, whereby the tool M will be reciprocated.

By means of my improved machine comparatively little power is required to operate the tool.

The tool M can have any suitable kind of bit or cutting-edge, and can be used for cutting or otherwise operating on stone, wood, metal, &c. The wheel J can be revolved by hand machinery or in any other suitable manner.

Having thus described my invention, I claim as new and desire to secure by Letters Patent—

1. In a tool-reciprocating machine, the combination, with two cylinders, each having an open and a closed end, and connected together by a tube, of pistons in the said cylinders provided with piston-rods projecting from the open ends of the cylinders, and a regulating valve in the connecting-tube, substantially as herein shown and described.

2. The combination, with two cylinders, each having an open and a closed end, the closed ends being connected by a tube, of a piston in each cylinder, a piston-rod on each piston, the piston-rods projecting from the open ends of

the cylinders, closed casings surrounding the cylinders, and a tube connecting the casings and surrounding the tube connecting the cylinders, substantially as herein shown and described.

3. In a tool-reciprocating machine, the combination, with the cylinders A C, the tube B, connecting the cylinders, and the valve O in the said tube, of the pistons E F, provided with rods E' F', and the guide-tube K, through which the piston-rod F' passes, substantially as herein shown and described.

4. In a tool-reciprocating machine, the combination, with the cylinders A C, the tube B, connecting the cylinders, and the valve O in the said tube, of the pistons E F, provided with piston-rods E' F', the guide-tube K, and the handle-piece A, surrounding the guide-tube, substantially as herein shown and described.

5. In a tool-reciprocating machine, the combination, with the piston-cylinders A C and the tube B, connecting them, of the valve O in said tube, substantially as herein shown and described.

FRED R. PATCH.
